UNITED STATES PATENT OFFICE

ALBERT F. PARKS, OF SOUTH NORWALK, CONNECTICUT, ASSIGNOR TO THE NORWALK COMPANY, OF SOUTH NORWALK, CONNECTICUT, A CORPORATION OF CONNECTICUT.

UNLOADER FOR COMPRESSORS.

Application filed August 15, 1924. Serial No. 732,237.

To all whom it may concern:

Be it known that ALBERT F. PARKS, a citizen of the United States, and resident of South Norwalk, in the county of Fairfield, and State of Connecticut, has invented certain new and useful Improvements in Unloaders for Compressors, of which the following is a specification.

The present invention relates to an improved compressor unloader, and has for an object to provide a device of this character adapted to be automatically actuated through the pressure in the receiver to maintain a predetermined operating pressure, irrespective of the variation in the consumption of the compressed medium, and which will be positive and reliable in operation.

Other objects are to provide a device of this character, which may be readily assembled and installed as a complete unit in the compressor, and which will be free of any parts that will readily get out of order.

With the above and other objects in view, embodiments of the invention are shown in the accompanying drawings, and these embodiments will be hereinafter more fully described with reference thereto, and the invention will be finally pointed out in the claims.

In the drawings:

Fig. 1 is a view partly in elevation and partly in vertical section of the high pressure cylinder side of a cross compounded multi-stage compressor, embodying the invention.

Fig. 2 is an end elevation thereof, partly in section;

Fig. 3 is a vertical sectional view of the inlet valve and unloader, according to one embodiment of the invention;

Fig. 4 is a plan view of the lifter forming part of the unloader;

Fig. 5 is a plan view of the inlet valve stop plate;

Fig. 6 is a vertical sectional view of a modified form of the device.

Referring to the drawings, the air compressor illustrated in Figs. 1 and 2, and in which the unloader devices according to the present invention are incorporated, is of the cross compounded multi-stage type, and comprises a low pressure cylinder 10

and a high pressure cylinder 11, in each of which a reciprocating piston 12 is arranged and operated through a piston rod 13 from a suitable source of power, as a motor driven eccentric. The low pressure cylinder is provided at each end with inlet valves, indicated generally as 14, in which the present unloader means are incorporated, and which admit air to the cylinder from the air space 15 surrounding the same at one side, air being admitted to this space through a pipe 16. The cylinder is also provided at each end with outlet valves 17 for releasing the compressed air from the cylinder to the space 18, and from which it is carried through the intercooler conduit 19 to the inlet space 20 of the high pressure cylinder.

The high pressure cylinder is provided at each end with an inlet valve, indicated as 14, having unloader means according to the present invention, for admitting the compressed air from the space 20 to the cylinder, and also provided at each end with outlet valves 17 for releasing the compressed air from the cylinder to the air space 21, and from which it is conducted by a pipe 22 to a receiver, not shown.

In the present illustration the pistons of the respective cylinders are attached to independent running gear, but it will be understood that the invention is adapted for use on any type of compressor, that is, a single cylinder machine, a multi-stage machine of the tandem type, and in which the two cylinders are in line and the pistons mounted on a single piston rod, or of the multi-stage type having more than two cylinders.

The unloader means, according to the invention, is incorporated in the inlet valves, and is adapted upon a predetermined pressure being produced in the receiver to be operated to open said valves, the valves being automatically closed when the pressure is relieved. For this purpose air is admitted under pressure to the unloaders through a series of pipe lines from the receiver, consisting in the example shown in Figs. 1 and 2 of a pipe 23 from the receiver connected to two control valves 24 and 25, which may be set for any predetermined operating pressure at which it is desirable for the unloader

to operate. The valve 24 is connected by a pipe 26 to the rear inlet valve of the high pressure cylinder and by a pipe 27 to the front inlet valve of the low pressure cylinder, while the valve 25 is connected by a pipe 28 to the rear inlet valve of the low pressure cylinder and by a pipe 29 to the front inlet valve of the high pressure cylinder.

10 Each valve is provided with a complete unloading mechanism and the total number of inlet valves is connected in parallel with the air lines, so that each valve may receive the identical operating pressure at the same instant. With this arrangement, as applied to the double acting compressor shown, the unloaders of the inlet valves of the high pressure cylinder are operated by the same means applied to the inlet valves of the low pressure intake cylinder, and in the same proportion on complementary ends of the compressing strokes, so that if one end of the intake cylinder be unloaded the proper end of the second stage cylinder is unloaded 25 in like amount. In this way the mechanical balance of the compressor is maintained and improved operating conditions gained by producing smoother operation.

15 The unloader, according to the present invention is shown in Figs. 3 to 6, Fig. 6 showing a slightly modified form of construction than that shown in Figs. 3 to 5.

20 The cylinder wall is provided with an air chamber 30 having a valve controlled port 31 provided with an annular valve seat shoulder 32, and in radial alignment with said port the outer wall of the chamber is provided with a circular opening 33 having an annular closure or bonnet seating shoulder 33^a. The inlet valve and unloader is adapted to be engaged and seated as a unit in said port 31 and opening 33.

25 The valve is of a type adapted to close during the compression stroke of the piston and open during the admission stroke, and comprises a cage consisting of a valve guard or stop member 34 having an annular flange 35 seated on the shoulder 32, and a valve seat member 36 provided with an annular flange 37, said seat having marginal closure contact with the stop member, a valve space 38 being provided between said stop and seat. The stop and seat are assembled to form a valve unit by means of an internal 30 threaded stud 39.

35 The stop member, shown in plan in Fig. 5, is provided with a plurality of annular inlet openings 40 having radial portions 41 forming connecting webs, and in the solid 40 portions between said openings there are provided, at suitably spaced points, a plurality of spring seats or pockets 42, in which are placed the valve springs 43 which press upwardly upon the valve ring members 44 having spaces 45 between them in register

with the openings 40 and being normally pressed against the valve seat.

40 The valve seat 36 is provided with a plurality of spaced and radially disposed inlet passages 46 out of register with the openings 40 of the valve stop and normally closed by the solid ring valve members 44 in the normally engaged position of the members with the seat. In operation the valve members are seated during the compression stroke of 45 the compressor piston to close the passages 46, while during the admission stroke the same is drawn against the stop, opening the inlet passages 46 and providing intake communication with the cylinder through the 50 registered valve ports 45 and the openings 40 of the stop.

55 The valve bonnet 47 which is engaged in the seat 34 against a sealing gasket 48 is secured by suitable bolts 49, and is provided with a central threaded opening 50 in which a locking stud or bushing 51 having wrench 60 engaging notches 52 is secured.

65 A valve retaining yoke comprising a relatively large ring 53 engaging the flange 37 65 of the valve seat member 36, a smaller ring 54 disposed beneath and engaged by the lower end of the stud 51, and radial connecting arms 55 between said rings, is pressed downwardly by the stud and clamps the 70 valve in place.

75 The upper end of the stud extends above the bonnet and has screwed therein the overhanging internally threaded nut portion 56 of a cylinder member 57 disposed 80 within and extending downwardly in the stud. The chamber 58 of the cylinder member has a reduced inlet passage 59 provided at its upper end with a threaded portion 60 for connection of the pressure pipe line 85 from the receiver. Within the chamber there is provided a plunger 61 having suitable packing rings 62, and at the lower end of the plunger within the space enclosed by the valve retaining yoke there is provided a 90 spider shaped valve lifter, comprising a central hub portion 63 and radial arms 64 having depending fingers 65 extending into the inlet passages 46 of the valve, a spring 66 engaged in a socket 67 of the hub 63 and bearing upon the valve seat member normally retaining the lifter in its raised or inoperative position, with the stop portions 68 of the arms abutting the ring 54 of the valve retaining yoke. An annular ring 69 95 is integrally formed between the arms 64 for strengthening, and also for cooperation with manually operable means, presently to be more fully referred to, for manually 100 opening the valve.

105 The operation of the device is as follows:

110 When the pressure in the receiver reaches the predetermined point at which the control valves 24 and 25 operate, air under 115 pressure is admitted to the chamber 58 and 120

the plunger is advanced to depress the valve lifter, which moves downwardly through the passages 46 and opens the valve, moving it against the stop member, where it is held until the pressure in the receiver has been reduced to a point at which the control valves 24 and 25 close, the spring 66 thereupon raising the valve lifter and plunger and permitting the valve to close.

10 Upon occasion it is desirable to open the valve manually, as when starting the compressor, and for this purpose a plurality, preferably four, equally spaced plungers 70 are mounted in vertical passages 71 of 15 the bonnet and are engaged in pockets 70^a in the ring 69 of the lifter, being limited in their upward movement by beveled shoulders 72 engaging beveled seats 73 in the under side of the bonnet. The upper ends 20 of the plungers project above the bonnet and are engaged by a hand lever 74 rotatably mounted upon a reduced portion 75 of the cylinder member and retained thereon by a nut 76 screwed upon said reduced portion, the lever being provided at suitably spaced points with beveled camming portions 77 adapted upon turning of the handle to depress the plungers, which in turn depress the lifter, thereby opening the valve. 25 Upon disengagement of the camming portions through further turning of the handle the lifter is permitted to raise under the pressure of the spring 66 and the valve closed.

25 In Fig. 6 there is illustrated a modified form of the invention in which the valve is of smaller diameter than that of the other form, and the arms of the lifter 78 are correspondingly shorter than those of the other form, being provided with two depending valve opening fingers rather than three. In this form, also, there is no manual operating means, the nut portion 79 of the plunger cylinder member being flat on top, as distinguished from the reduced end portion in the other form. It will be understood, of course, that manual operating means could be incorporated in this form in the same manner as disclosed in Fig. 3.

50 I have illustrated and described preferred and satisfactory embodiments of the invention, but it will be understood that changes may be made therein, within the spirit and scope thereof, as defined in the appended claims.

Having thus described my invention, what I claim and desire to secure by Letters Patent is:

1. In combination with an inlet valve of a 60 compressor, a pressure actuated unloader comprising a valve lifter, a plunger for depressing said lifter, a pressure cylinder in which said plunger operates, a support surrounding said cylinder, valve retaining 65 means interposed between said support and

the valve for securing the valve upon its seat, and means adjustable through the support for mounting the cylinder and engaging the valve retaining means to hold it against casual movement. 70

2. In combination with an inlet valve of a compressor, a pressure actuated unloader comprising a valve lifter, a plunger fixedly secured to said lifter for depressing the same, a member including a pressure cylinder in which said plunger operates, a support surrounding said member and cylinder, said member having a portion extending at the opposite side of the support from that at which the valve is located, manually operable means for depressing the valve lifter and including a lever mounted on the extension of said member, and valve retaining means interposed between said support and the valve for securing the valve upon its seat. 80

3. In combination with an inlet valve of a compressor, a pressure actuated unloader comprising a valve lifter, a plunger for depressing said lifter, a member including a pressure cylinder in which said plunger operates, an annular valve retainer surrounding said lifter and engaging said valve at its marginal portion to secure it upon its seat, and means adapted to press said retainer in engagement with said valve, said means surrounding and supporting said member and being rotatable into and out of engagement with the retainer. 90

4. In combination with an inlet valve of a compressor, a pressure actuated unloader comprising a valve lifter, a plunger for depressing said lifter, a pressure cylinder in which said plunger operates, a valve retainer engaging said valve to secure it upon its seat, a support annularly surrounding said cylinder, a cylindrical externally threaded member engaged in said support, said pressure cylinder being supported and extending downwardly in said member, said member being engaged at its lower end with said valve retainer to press the same in engagement with said valve. 105

5. In combination with an inlet valve of a compressor, a pressure actuated unloader comprising a valve lifter, a plunger for depressing said lifter, a pressure cylinder in which said plunger operates, an annular valve retainer surrounding said lifter and engaging said valve at its marginal portion to secure it upon its seat, a support for said cylinder, and means on said support engaging said valve retainer in annularly and outwardly spaced relation to said cylinder and adapted to press said retainer in engagement with said valve. 110

6. In combination with an inlet valve of a compressor, a pressure actuated unloader comprising a valve lifter, a plunger for depressing said lifter, a pressure cylinder in 125

130

which said plunger operates, and manual means directly engaged with said lifter for manually depressing it independently of the plunger.

- 5 7. In combination with an inlet valve of a compressor, a pressure actuated unloader comprising a valve lifter, a plunger for depressing said lifter, a pressure cylinder in which said plunger operates, a support for
- 10 said cylinder annularly surrounding the same, plungers operating through said support directly engaging said lifter, and man-

ual means for operating said plungers to manually operate the lifter.

8. In combination with an inlet valve of a compressor, an unloader comprising a valve lifter, means for depressing said lifter, said means including plungers directly engaging said lifter at equally spaced points about its center, and means for manually depressing the plungers.

Signed at Bridgeport this 11th day of Aug., 1924.

ALBERT F. PARKS.
